HENRY LOEHR, OF BOSTON, MASSACHUSETTS.

Design No. 3,459, dated April 27, 1869.

DESIGN FOR A HEARSE.

The Schedule referred to in these Letters Patent and making part of the same.

To all whom it may concern:

Be it known that I, HENRY LOEHR, of Boston, in the county of Suffolk, and State of Massachusetts, have originated and designed a new Ornament or Figure for Hearses, or Hearse-Carriages, of which the following is a full, clear, and exact description, reference being had to the accompanying drawings, making a part of this specification.

The ornament which I would apply to hearses, or hearse-carriages, consists of figures of angels, one standing at each corner of the hearse, in the manner represented in the accompanying drawing.

These figures are carved from wood, of life or suitable size, or made of hollow metal, or any suitable material, moulded, sculptured, or cast in the form of angels, and made fast to each corner of the carriage, in an upright or other posture, holding in the hand a torch or other suitable emblem of death. The angels may be of different colors—of white or silvered, when the carriage is to be used for conveying the bodies of

the young or unmarried deceased, or gilded, as the more emblematic of the deceased husband or wife, and different hearses may be used, as occasion requires.

These figures may also be draped or decked with flowers or other appropriate ornaments, thereby producing a very pleasing effect.

Plumes of various colors are used on the corners of hearses, but the full figures of angles, in the position and adorned as above described, are new and original designs as applied to hearses.

What I claim as my invention, and desire to secure by Letters Patent, is—

The design of a hearse, or hearse-carriage, adorned with the figures of angels, one standing at each corner of the hearse, as above set forth.

HENRY LOEHR.
